United States Patent Office.

JOHN MARTINO, JACOB BEESLEY, AND JOHN CURRIE, OF PHILADELPHIA, PENNSYLVANIA, ASSIGNORS TO ABBOTT & NOBLE, OF SAME PLACE.

Design No. 3,190, dated September 1, 1868.

DESIGN FOR PLATES FOR PORTABLE RANGES.

The Schedule referred to in these Letters Patent and making part of the same.

TO ALL WHOM IT MAY CONCERN:

Be it known that we, JOHN MARTINO, JACOB BEESLEY, and JOHN CURRIE, of Philadelphia, county of Philadelphia, State of Pennsylvania, have invented or produced a new and original Design for the Plates for a Portable Range; and we do hereby declare that the accompanying drawing, and the following explanation thereof, form a full, clear, and exact description of the said design.

Figure 1 is the oven-door.

Figure 2, a smaller door or panel.

Figure 3, a plan view of the front end of the bottom plate.

Figure 4, a plate in front of the ash-pit, and

Figure 5 a plate in front of the fireplace.

The oven-door has a central oval ornament, of the character clearly shown in the drawing, foliated ornaments, *a*, and other foliated ornaments, *a'*, near the corners.

The smaller door or panel, fig. 2, has, besides the central ornament and foliated ornaments *a'*, a beading, *b*, of alternate bars and dots.

The bottom plate has an ornamental beading, *c*, clearly shown in the drawing.

In the centre of the ash-pit plate, fig. 4, is a register, on which are foliated ornaments, *d*, similar to those represented by *a'* in fig. 1. This plate has also other ornaments, *e*, and beadings, *b* and *f*.

The fireplace-plate, fig. 5, has merely the beading *b*.

We claim the design for the plates of a portable range, substantially as herein described and represented in and by the accompanying drawing.

In testimony whereof, we have signed our names to this specification in the presence of two subscribing witnesses.
